(57) **CLAIM**

The ornamental design for an illuminated handle, as shown and described.

DESCRIPTION

FIG. 1 is a front perspective view of the illuminated handle showing my new design;

FIG. 2 is a rear perspective view thereof;

FIG. 3 is a top plan view thereof;

FIG. 4 is a left side elevational view thereof;

FIG. 5 is a bottom plan view thereof; and,

FIG. 6 is a right side elevational view thereof.

The broken line circle at the end of the handle in FIGS. 1-3 and 5 illustrates a portion of the handle which forms no part of the claimed design.
